UNITED STATES PATENT OFFICE.

FRANK X. SCHUMAKER, OF FORT SCOTT, KANSAS.

HARNESS.

No. 908,891.

Specification of Letters Patent.

Patented Jan. 5, 1909.

Application filed June 15, 1908. Serial No. 438,562.

To all whom it may concern:

Be it known that I, FRANK X. SCHUMAKER, citizen of the United States, residing at Fort Scott, in the county of Bourbon and State of 5 Kansas, have invented new and useful Improvements in Harness, of which the following is a specification.

My invention relates to improvements in harness; and it consists in a breast-collar and 10 a trace connected through the medium of the peculiar and advantageous means herein-after described and particularly pointed out in the claim appended.

In the drawings accompanying and forming part of this specification: Figure 1 is a 15 view illustrating a breast-collar and a trace properly positioned on a horse and connected together through the medium of my improvements. Fig. 2 is a horizontal section taken 20 through the longitudinal center of the breast-collar, the trace and my improvements; said view being on an enlarged scale. Fig. 3 is a perspective view of the metallic link comprised in my improvements, removed.

Similar letters designate corresponding 25 parts in all of the views of the drawings, referring to which:

A is a breast-collar which is made wide in 30 the conventional manner in order to avoid cutting or chafing of a horse's breast. In accordance with my invention the said collar is formed of a single strap tapered toward its end, as indicated by a, and on the outer side 35 of the end portion of the strap is provided a loop B, preferably of leather, which is stitched or otherwise connected to the strap and has its bight disposed in rear of the end of the strap, as indicated by b and best shown in Fig. 2. The breast-collar is also provided, 40 by preference, with one or more tugs C for the connection of the usual or any other approved means for suspending the breast-collar in position.

D is a trace having a loop c at its forward 45 end, and E is the metallic link through which the loop B and the looped end c of the trace are connected together. The said link E is rectangular in outline, and is provided with parallel upright bars d and a vertical central 50 bar e. Thus it will be manifest that the link

has two eyes f and g of equal size, and it will also be manifest that when the parts are assembled as shown in Figs. 1 and 2, the said eyes snugly receive the bights of the loops B and c, with the result that all of the link is 55 hidden from view except the upper and lower end bars and the vertical central bar e thereof, and a neat and finished connection is effected between the breast-collar and the trace, and one calculated to enhance the general finished 60 appearance of a harness. It will also be noted that the said connection is a strong and durable one and is of such a nature that the trace D is free to swing outward and inward on its respective link bar without any 65 tendency whatever of the breast-collar being moved laterally away from or toward the body of the horse. The vertical-central bar e of the link is specifically advantageous because it serves, by reason of its location to 70 lend equal strength to the vertical side bars d. It will be further gathered from the foregoing that the breast-collar A may, by virtue of my improvements, be made of a comparatively short strap, and consequently but a 75 minimum amount of waste will be entailed in reducing the end portion of the strap to substantially the same width as the trace D.

I have shown but one end portion of the breast-collar A and but one trace, but it will 80 be understood that both ends of the breast-collar will be connected with traces in the manner herein illustrated and described.

It is old in harness to provide a breast-collar with buckles at its ends for the detachable connection of traces. It is also old to connect a loop on a tug section and a loop on a trace section through a link having parallel bars disposed in the loops of the sections.

I make no claim to anything in common 90 with the above defined constructions, but

What I claim and desire to secure by Letters-Patent, is:

In a harness, a link formed in one piece and having parallel, vertical side bars, a vertical-central bar, and end bars connecting the ends of the side bars and vertical-central bar, in combination with a breast-collar having a loop which permanently receives the forward side bar of the link and extends from one end 100

bar thereof to the other, and a trace having a loop which permanently receives the rear side bar of the link and also extends from one end bar thereof to the other; the bights of the 5 said loops being arranged at opposite sides of and adjacent the vertical-central bar of the link.

In testimony whereof I have hereunto set my hand in presence of two subscribing witnesses.

FRANK X. SCHUMAKER.
